UNITED STATES PATENT OFFICE

147,304

DESIGN FOR A COVERED PITCHER

Jacob L. Sager, Smithton, Pa.

Application April 15, 1947, Serial No. 138,421

Term of patent 14 years

(Cl. D44—21)

To all whom it may concern:

Be it known that I, Jacob L. Sager, a citizen of the United States, residing at Smithton, in the county of Westmoreland and State of Pennsylvania, have invented a new, original, and ornamental Design for a Covered Pitcher, of which the following is a specification, reference being had to the accompanying drawing, forming part thereof.

Figure 1 is a perspective view of the covered pitcher of my new design;

Figure 2 is a front elevational view thereof; Figure 3 is a side elevational view thereof;

Figure 4 is a rear elevational view thereof; and Figure 5 is a top plan view thereof.

I claim:

The ornamental design for a covered pitcher, as shown.

JACOB L. SAGER.
